DESIGN FOR A COMBINED RADIO AND PHONOGRAPH CABINET OR THE LIKE

Henry W. Gerard, New York, N. Y., assignor to
Sonora Electric Phonograph Co., Inc., New
York, N. Y., a corporation of New York

Application March 6, 1937, Serial No. 68,049

Term of patent 7 years

To all whom it may concern:

Be it known that I, Henry W. Gerard, a citizen
of the United States, residing in New York, county
and State of New York, have invented a new,
original, and ornamental Design for a Combined
Radio and Phonograph Cabinet or the like, of
which the following is a specification, reference
being had to the accompanying drawing forming
a part thereof.

In the drawing:—

Fig. 1 is a perspective view of a combined radio
and phonograph cabinet showing my design.

Fig. 2 is a perspective view similar to Fig. 1
showing a part of the top in open position.

I claim:—

The ornamental design for a combined radio
and phonograph cabinet or the like as shown.

HENRY W. GERARD.
